McCormack & Heuser[57] **CLAIM**

The ornamental design for a planter, as shown and described.

DESCRIPTION

FIG. 1 is a front elevational view of planter showing my new design, the rear view (not shown) being identical thereto;

FIG. 2 is a right side elevational view, the left side (not shown) being a mirror image thereof;

FIG. 3 is a top plan view;

FIG. 4 is a bottom plan view; and,

FIG. 5 is a perspective view.

The broken lines of FIG. 5 showing arrangements of flowers and plants, and soil, are for illustrative purposes only and form no part of the claimed design.

FIG. 5

FIG. 4

FIG. 3

FIG. 2

FIG. 1
